BORING MOTOR

Theo Seifer, Berlin, Germany

Application November 1, 1935, Serial No. 47,891
In Germany September 23, 1933

9 Claims. (Cl. 255—4)

This invention relates to motors adapted to work in a bore-hole by means of the flushing fluid, more especially to such motors in which the bit is reciprocated in vertical direction by the flushing fluid, the flow of which is controlled by means of a valve or valves actuated by springs.

The control valves of such motors as hitherto used are opened when the tension of a spring has increased to a certain extent. According to the present invention the action of the springs of the valves is controlled by a bolting device influenced by the parts of the motor moving against one another. Hereby it is possible to store in the valve spring a quite greater tension than in the well-known motors. Therefore the opening of the valve constructed according to the invention is accelerated and the number of strokes of the motor per unit of time is increased. Furthermore the motor can be made to work with uniform and exactly adjustable height of the stroke, whereas the working and the height of the stroke of the usual motors is liable to vary, because the spring is only compressed by the hydraulic pressure of the streaming flushing fluid and the friction in the moving parts of the motor. This friction, however, is subjected to considerable variations.

In the annexed drawings different modifications embodying the invention are illustrated in connection with a motor in which the chisel is suspended from the cylinder moving upwards and downwards, the valve cooperating with an annular valve surface in a plane approximately perpendicular to the axis of the bore tubing.

Fig. 1 is a vertical longitudinal cross-section, partly an elevation of a boring mechanism constructed according to the invention, the valve being closed.

Fig. 2 is a similar view showing the mechanism with the valve opened.

Figs. 3 and 5 are perspective views, and Fig. 4 is a horizontal cross-section on the line IV—IV of Fig. 3, these three figures showing a modification.

Fig. 6 represents another modification.

Figs. 7 and 8 illustrate a further modification.

Figs. 9 and 10 show in vertical and horizontal cross-section respectively a further modification, and

Fig. 11 is a detail showing in vertical cross-section still another modification.

The same reference letters are used to designate corresponding parts throughout all the figures.

Referring first to Figs. 1 and 2, *a* is the tubing through which the flushing fluid flows, *b* the cylinder of the hydraulic motor connected with the chisel *c*. *d* is a piston-like enlargement of the tubing *a*, on which the cylinder *b* may slide upwardly and downwardly; this piston separates the cylinder space into two parts. *e* is an opening in the tubing *a* for introducing the flushing fluid into the upper part of the cylinder and *f* is another opening in the tubing *a* for introducing the flushing fluid into the lower part of the cylinder. Between the openings *e* and *f* a valve is provided in the tubing *a*, the valve body *g* being secured to the rod *h*. A collar *i* is provided on the valve rod *h*, and a second collar *k* is fixed at the free end of the rod *h*. A cylinder *l* having a smaller diameter than the cylinder *b* is coaxially and rigidly connected with the latter. In its interior the cylinder *l* carries an annular projection *m*, and at its exterior upper and lower end it is provided with collar-like thickened portions *n*. With the lower portion of the tubing the levers *o* are pivotally connected cooperating by rests *p* with the collar *i* and sliding with rolls *q* on the outer surface of the cylinder *l*. *r* and *s* are the control springs of the valve.

t in Figs. 1, 2, 5, 7, 8, 9 and 10 is a spring keeping the levers *o* in locking position. *u* are openings near the bottom of the cylinder through which the flushing fluid is allowed to flow off towards the chisel.

The motor works as follows:

When the valve is in the closing position, the flushing fluid flows from the tubing *a* through the opening *e* into the upper space of the cylinder *b* lifting thereby the cylinder with the chisel and compressing the control spring *r*, the latter bearing, on the one hand, against the rising collar *m* of the cylinder *l* and, on the other hand, against the collar *i* assuming with the valve rod and the valve *g* an idle position, because the rests *p* of the levers *o* are located above the collar *i* acting as an abutment. While the cylinder *b* is lifted (Fig. 2) finally the lower thickened portion *n* of the cylinder *l* attains the rolls *q*, which will swing against the action of the spring *t* towards the wall of the cylinder *b* releasing the collar *i* so that the latter is projected upwards by the spring *r* and valve *g* is opened.

Now the flushing fluid is allowed to flow through the openings *e*, *f*, *u* to the chisel *c* flushing away the cuttings produced by the chisel in the foregoing stroke. The cylinder *b* with the chisel *c* sinks down by its own weight and the rolls *q* again run on the thinner portion of the cylin-

der *l* the levers *o* swing under the action of the spring *t* inwardly, and the rests *p* of the levers *o* lock the valve rod *h* beneath the collar *i*. The cylinder *b*, including the heavy bar *z* and the chisel *c* continues to drop down compressing the spring *s* which on the one hand bears against the lowering collar *m* and, on the other hand, against the collar *k*, the collar *i* being retained by the abutments *p*. As soon as the rolls *q* rise upon the upper thickened portion of the cylinder *l* the levers *o* are forced to swing outwardly and, the abutments *p* are lifted beneath the collar *i* in the same way as on opening the valve, and the spring *s* closes the valve *g*. Then the play of the 15 motor begins anew.

The modifications shown in Figs. 3-11 differ only in the construction of the locking means *o*, *p* and *q* for the collar *i* on the valve rod *h*, the other parts of the motor being only so slightly modified that no special explanation of these 20 parts common to all modifications seems necessary.

In the modification shown in Figs. 3 to 5 sleeves *v* rotatable on rods *o'* are provided instead of the levers *o*, which sleeves are equipped with abutments *p* and rolls *q* similar to those connected with the levers *o* in Figs. 1 and 2, by means of which the valve is released in such a way that when the rolls *q* run along the cam-like thickened portions of the cylinder *l* the abutments *p* are brought into or out of engagement with the stop *i* on the valve rod *h*. The springs *r* and *s* in this case act in the same manner as described above and shown in Figs. 35 1 and 2.

In the modification shown in Figs. 1, 2 and 5, the rolls *q* are held pressed against the guiding faces *n* by a spring *t*. This spring may be replaced by other means forcibly guiding the rolls 40 *q*, f. i., by providing not only one roll, but a pair of rolls on each sleeve *v* as shown in Fig. 4 so that the one roll runs in a recess of the cylinder *l* while simultaneously the other roll runs on the thickened portion of the cylinder, whereas 45 reversely when the first roll attains the thickened portion of the cylinder *l* the other roll of the pair attains the recess of the cylinder *l*. In this way the rolls *q* work forcibly together with the cylinder *l*.

50 In the modification shown in Fig. 6 the rolls *q* are likewise forcibly guided, the spring *t* being avoided and only a single roll being provided which is guided in this case between the sloping surfaces *w* provided on the inner wall of the 55 motor cylinder *b* and the outer wall of the inner cylinder *l*.

In the modification shown in Figs. 9 and 10 the swinging levers *o* of Figs. 1 and 2 are combined with the rotatable sleeves of Figs. 3 to 5. 60 On displacing the cylinder with respect to the stationary tubing the inner sloping surface of the levers *o* will bring the levers *p'* (Fig. 10) out of engagement with the collar or abutment *i* thereby releasing the closing spring. The 65 abutments *p'* are here shaped to form levers swinging around a perpendicular axis, exactly as shown in Figs. 3 to 5.

The modification illustrated in Fig. 11 differs from that shown in Fig. 9 only by the levers *p*² 70 forming the rests swinging around horizontal instead of perpendicular axes. It enables a shorter, more compact structure than the modification represents by Figs. 7 and 8.

75 It is understood that in the springs *r* or *s* any desired excess of power can be stored up to the

point where the rolls run upon the lower or upper thickened portion of the cylinder *l* so that a very sudden opening or closing of the valve *g* can be accomplished and a rapid flow of the flushing fluid to the chisel can be effected. By varying the distance between the upper and the lower thickened portions *n* of the cylinder *l* the stroke of the auger may be exactly determined.

In order to increase the duration of the control springs, their length is calculated in such a manner that they are not wholly released in their end position, for it has been ascertained that the duration of the springs is increased by taking care that they are not wholly released after each stroke or swing beyond the state of complete release. It is also possible to provide longer springs or normal springs and abutments *x* on the rod *h* (Figs. 7 and 8) which are retained at the abutment *x* by dishes *y* freely movable on the valve rod *h*, the abutment *x* being allowed to slide through the annular projection *m* in the inner cylinder *l*.

I claim:—

1. In a motor working in a bore-hole by means of a flushing fluid, a tubing, a piston rigidly connected therewith, a cylinder adapted to slide over the said piston, a chisel suspended from the said cylinder, a valve in the said tubing, a rod carrying the body of the valve, an abutment on the said rod, levers pivotally connected with the tubing, rests provided on the said levers adapted to engage the said abutment alternately from both sides, a second abutment on a moving part of the motor, a spring between both abutments, a disk at the end of the said rod, a spring between the disk and the first named abutment, and cams provided on a moving part of the motor cooperating with the said levers.

2. In a motor working in a bore-hole by means of a flushing fluid, a tubing, a piston rigidly connected therewith, a cylinder adapted to slide over the said piston, a chisel suspended from the said cylinder, a valve in the said tubing, springs arranged to open and to close said valve under the action of a moving part of the motor, a rod carrying the body of the valve, an abutment on the said rod, sleeves rotatably connected with the tubing and carrying rests adapted to engage the said abutment alternately from both sides, rolls mounted on the said sleeves, and a member rigidly connected with the cylinder and carrying cams cooperating with the said rolls.

3. In a motor working in a bore-hole by means of a flushing fluid, a tubing, a piston rigidly connected therewith, a cylinder adapted to slide over the said piston, a chisel suspended from the said cylinder, a valve in the said tubing, springs arranged to open and to close said valve under the action of a moving part of the motor, a rod carrying the body of the valve, an abutment on the said rod, sleeves rotatably connected with the tubing and carrying rests adapted to engage the said abutment alternately from both sides, rolls mounted on the said sleeves, a member rigidly connected with the cylinder and carrying cams 55 cooperating with the said rolls and springs tending to keep the said rests and rolls in engagement with the said abutment and cams.

4. In a motor working in a bore-hole by means of a flushing fluid, a tubing, a piston rigidly connected therewith, a cylinder adapted to slide over the said piston, a chisel suspended from the said cylinder, a valve in the said tubing, springs arranged to open and to close said valve under the action of a moving part of the motor, a smaller 70

cylinder concentrically arranged in the motor cylinder and rigidly connected therewith, a sloping shoulder on the inner wall of the motor cylinder, sloping shoulders on the outer wall of the 5 smaller cylinder, and valve controlling members connected with the tubing and cooperating with the said shoulders.

5. In a motor working in a bore-hole by means of a flushing fluid, a tubing, a piston rigidly connected therewith, a cylinder adapted to slide over the said piston, a chisel suspended from the said cylinder, a valve in the said tubing, springs arranged to open and to close said valve under the action of a moving part of the motor, a rod carrying 10 the body of the valve, an abutment on the said rod, sleeves rotatably connected with the tubing and carrying rests adapted to engage the said abutment alternately from both sides, pairs of rolls mounted on the said sleeves, and a member rigidly connected with the cylinder and carrying 15 pairs of cams staggered with respect to one another cooperating with the said rolls.

6. A device in accordance with claim 7, in which abutments are provided on which the control spring and the moving part of the motor, contiguous to the spring up to its final position, strikes before the spring is completely released.

7. In a hydraulic motor working in a bore-hole by means of a flushing fluid, a hollow tubing, a piston fixed on the tubing, a cylinder adapted to slide upwards and downwards on the said piston, a chisel suspended from the said cylinder, an outlet opening at the lower end of the tubing, a valve above the said opening adapted to close 20 and open the latter, springs adapted to be compressed by the upward stroke of the cylinder and to open the said valve, a rod carrying the body of the valve, an abutment on the said rod, levers pivotally connected with the tubing, rests provided on the said levers adapted to engage the said abutment alternately from both sides, and cams provided on a moving part of the motor cooperating with the said levers.

the valve and setting the springs free in a pre-determined relative position of the cylinder and the piston.

8. In a hydraulic motor working in a bore-hole by means of a flushing fluid, a hollow tubing, a piston fixed on the tubing, a cylinder adapted to slide upwards and downwards on the said piston, 5 a chisel suspended from the said cylinder, an outlet opening at the lower end of the tubing, a valve above the said opening adapted to close 10 and open the latter, springs adapted to be compressed by the upward stroke of the cylinder and to open the said valve, a rod carrying the body of the valve, an abutment on the said rod, levers pivotally connected with the tubing, rests provided on the said levers adapted to engage the said abutment alternately from both sides, and cams provided on a moving part of the motor 15 cooperating with the said levers.

9. In a hydraulic motor working in a bore-hole by means of a flushing fluid, a hollow tubing, a piston fixed on the tubing, a cylinder adapted to slide upwards and downwards on the said piston, 20 a chisel suspended from the said cylinder, an outlet opening at the lower end of the tubing, a valve above the said opening adapted to close 25 and open the latter, springs adapted to be compressed by the upward stroke of the cylinder and to open the said valve, a rod carrying the body of the valve, an abutment on the said rod, levers pivotally connected with the tubing, rests provided on the said levers adapted to engage the said abutment alternately from both sides, a tension 30 spring connecting the said levers, sliding members at the ends of the said levers, and cams 35 provided on a moving part of the motor cooperating with the said levers.

THEO SEIFER.
